UNITED STATES PATENT OFFICE

152,904

DESIGN FOR A TRICYCLE

Carter E. Quisenberry, Kirkwood, N. Y., assignor
to Car-Mac Mfg. Co. Inc., Binghamton, N. Y.,
a corporation of New York

Application July 24, 1947, Serial No. 140,488

Term of patent 14 years

(Cl. D34—15)

To all whom it may concern:

Be it known that I, Carter E. Quisenberry, a citizen of the United States, residing at town of Kirkwood, in the county of Broome and State of New York, have invented a new, original, and ornamental Design for a Tricycle, of which the following is a specification, reference being had to the accompanying drawing, forming part thereof.

In the drawing

Fig. 1 is a side perspective view of a tricycle showing my new design; and

Fig. 2 is a front elevation thereof.

The opposite side of the device is the same as that shown in Fig. 1.

The characteristic features of my design reside in the portions shown in full lines in the drawing.

I claim:

The ornamental design for a tricycle, as shown and described.

CARTER E. QUISENBERRY.
